UNITED STATES PATENT OFFICE.

GEORGE W. FERGUSON, OF WHITE PLAINS, NEW YORK, ASSIGNOR OF ONE-HALF TO
ANDREW F. KNAPP, OF WHITE PLAINS, NEW YORK.

COLLAPSIBLE SHEET-METAL BARREL.

1,182,466.

Specification of Letters Patent. Patented May 9, 1916.

Application filed July 28, 1914. Serial No. 853,704.

To all whom it may concern:

Be it known that I, GEORGE W. FERGUSON, a citizen of the United States, residing at White Plains, in the county of Westchester and State of New York, have invented certain new and useful Improvements in Collapsible Sheet-Metal Barrels, of which the following is a specification.

This invention relates to a sheet metal receptacle of the barrel type which is so constructed that it may be taken to pieces after being emptied and thus returned to the shipper in a knock-down condition.

The principal object of the invention is to provide a sheet metal barrel which may be securely held in the set up position and to provide improved means for holding the heads of the barrel in a locked position when the barrel is set up.

Another object of the invention is to so connect the heads with the body portion of the barrel so that they may be easily removed when desired and quickly connected when in use.

This invention is illustrated in the accompanying drawings, wherein—

Figure 1 is a side elevation of the improved barrel; Fig. 2 is a top plan view of the barrel; Fig. 3 is a vertical sectional view through the barrel; Fig. 4 is a transverse sectional view through the barrel.

The body portion or walls 10 of this barrel is formed from a strip of sheet metal which has its lower edge portion bent to 35 form an internal flange 11 shown in Fig. 3 and forming a pocket, the object of which will be hereinafter brought out. The upper edge portion of the body portion is bent back upon itself as shown at 12, thus forming a smooth edge and preventing danger of the person handling the barrel cutting his hands upon the upper edge of the barrel. The side edges of the strip from which the body portion is made are bent to form the hooks 13 and 14 which interlock as shown in Fig. 4 so that the side edge portions may be releasably connected and the body portion of the barrel held in the set up position.

The lower head 15 is formed from a sheet metal disk which is stamped to provide reinforcing ribs 16 and an annular flange 15'

which fits into the pocket formed by the internal flange 11. The upper head 17 is also formed from a sheet metal disk which is stamped to form strengthening ribs 18 similar to the ribs 16 and an annular flange 19. This head 17 is placed in the upper end of the barrel after the barrel has been filled and rests upon the supporting tongues 20 which are struck from the body portion 10. The 60 clamping tongues 21 which are also struck from the body portion 10 are now bent inwardly over the flange 19 and into engagement with the head 17, thus securely clamping the head in place and holding it in tight 65 engagement with the supporting tongues 20. When it is desired to empty the barrel, the tongues 21 are bent upwardly and the cover can then be removed. After the barrel has been emptied, the body portion is moved 70 to release the hooks 13 and 14 and the body portion will then open a sufficient amount to permit a number of the body portions to be placed one within the other thus permitting 75 bundles which may be packed in a freight car. By having the body portion formed of resilient material the bundles of body portions will not be liable to slip out of place and therefore the bundles do not have to be very tightly tied. It is of course obvious 80 that if the hooks 13 and 14 cannot be easily released while the head 15 is in place, this head may be first removed.

What is claimed is—

A receptacle of the character described 85 comprising a body portion, a lower head for said body portion, the upper edge portion of said body portion being bent to provide a bead, tongues struck from said body portion beneath said bead, an upper head for said 90 body portion, certain of said tongues being bent inwardly beneath said upper head and the remaining tongues being bent inwardly to engage said upper head and hold the same in engagement with the first mentioned 95 tongues.

In testimony whereof I affix my signature in presence of two witnesses.

GEO. W. FERGUSON.
